DECALCOMANIA AND METHOD OF MAKING THE SAME

Application filed October 21, 1929. Serial No. 401,064.

The invention relates to decalcomania which shall be capable of transferring designs executed in bold relief as distinguished from the now existing decalcomanias where the design is practically flat. The object of the invention is to provide a means by which, by a decalcomania process, designs of sharply embossed appearance can be applied to objects adapted to carry decalcomania designs, such as articles of furniture, wood, metal, glass, porcelain, etc. So far as I am aware, the decalcomania art has not, prior to my invention, been able to furnish any practical means for enabling the transferred design to appear in bold relief. My invention accordingly results in a combination which produces an entirely new and very ornamental type of decalcomania.

The invention is illustrated in the accompanying drawings in which Fig. 1 is a plan view of a decalcomania transfer sheet embodying my invention; Fig. 2 is an exaggerated sectional view taken on lines 2—2 of Fig. 1; Fig. 3 shows the design of Fig. 1 transferred to a bottle, while Fig. 4 is a sectional view taken on line 4—4 of Fig. 3 of the front portion of the bottle carrying the applied design. In Fig. 4 as in Fig. 2 the cross-sectional dimensions of the constituents of the transferred decalcomania have been exaggerated for the sake of clearness. Figs. 5 and 6 represent exaggerated sections of modifications of the decalcomania shown in Figs. 1 and 2.

As shown in Fig. 2, the decalcomania of this invention comprises a sheet of simple decalcomania paper 1, such as is used in the trade generally, having a water-soluble coating 2 of starch and gum. Above the layer 2 is a coating 3 of clear or colored transparent or opaque white or colored lacquer. The physical components of those parts of the design which possess the effect of bold relief, are indicated at 4. The design as shown in Fig. 1 appears on the transfer sheet in positive printing. In other words, the decalcomania belongs to the class of positive decalcomanias, to wit, that type of transfer on which the various colors as visible to the eye when the design is transferred, are printed right side

up. This is in contrast to the negative type of transfer where the colors are printed in the reverse order and the design becomes visible in its true colors only after the transfer has been applied and the backing paper removed. 55

When it is desired to transfer the design of the decalcomania shown in Fig. 1 to some article to which it is to be applied, for example the bottle illustrated in Fig. 3, the decalcomania shown in Figs. 1 and 2 is simply dipped 60 in water which dissolves the water-soluble adhesive 2 and permits the film 3 and the raised portions 4 thereon to be slid off the paper 1 on to the article to which the design is to be applied, the moist adhesive still carried by the film 3 serving simultaneously as an adhesive to unite the transfer film 3 with the bottle or other article to which the design is thus transferred.

Decalcomanias embodying my invention 70 may be manufactured in the following manner: A sheet of simple decalcomania paper such as is now generally used for decalcomanias and having a water-soluble coating of starch and gum, is first covered with a layer 75 of lacquer. This lacquer coating may be opaque, white or colored, but is preferably made of clear or colored transparent lacquer because this makes those portions of the design which stand out in bold relief more 80 prominent and decorative. The layer 3 may, however, be produced by successive printings of oil colors of any desired shade, but in that case the layer would be confined to the area only which comprises the design, the remainder of the sheet being left blank, all as illustrated in Fig. 5.

If there are any portions of the design, ornamentation, or lettering that are to remain flat, they are printed first after the film 3 90 of the desired strength and thickness has been associated with the adhesive 2 of the decalcomania paper 1. After all those parts of the design except the portions that are subsequently to appear in relief have been printed or lithographed, the sheet is allowed to become dry and hard. Thereupon the portions of the design which are to appear in relief are printed or lithographed in any suitable color, the only special requirement be- 100

ing that the ink used must be of a sticky nature for best results, although ordinary printing or lithography inks may be used for the purpose. While these last ink impressions, 5 representing the raised portions of the design, are still fresh, a compound of rosin is dusted on the print. Some of the particles of the rosin will adhere to the wet ink and the surplus shaken or blown off, leaving the rosin 10 only in the places which are subsequently to appear in relief. Various compounds can be used for this purpose, all of which can be obtained in the open market. The rosin compounds may be mixed with gold, silver, or 15 bronze, dry colors, etc., to produce various effects.

The sheet is now introduced into a heating chamber where a sufficient degree of heat is maintained to bring the rosin compound to 20 the melting point, after which the sheet is immediately withdrawn and cooled. As the result of this treatment the fine particles of the rosin compound, plus any pigment of the wet ink of the printed design or the colors 25 which may have been admixed with the rosin compound, form consolidated masses (as shown in Figs. 2 and 4) standing in both relief and corresponding with precision to the outlines of the raised portions of the design, no matter how delicate. The degree of 30 relief may be varied and is a function of fineness or coarseness of the rosin compound. For very fine and narrow lines a fine compound is used, as the coarser particles would 35 not satisfactorily adhere to the fine lines. On the other hand, a broad or bold design requires a coarser compound, since the fine compound used on a bold design frequently 40 does not deposit sufficient rosin to produce a bold relief when the compound is brought to a melting point.

Heretofore all positive decalcomania has been printed flat. Embossing is not practical in decalcomania since the raised portions 45 would flatten out in the transferring operation when water is applied and the backing paper removed. To attempt to build up a raised design by successive printings of white lead or the like with a final printing in colors, 50 is neither practical nor can it be carried out in such a way as to produce the effect of a bold relief. According to my new process, the decalcomania is produced as a positive decalcomania with those portions which are 55 to appear in bold relief not built up by successive layers, but constituted of homogeneous masses of fused rosin compound, the result of the application of a rosin-fusing heat applied to the otherwise completely finished 60 positive decalcomania, including the decalcomania paper, the adhesive, and the carrying layer for the raised parts of the design. By the new process the raised portions of the 65 design are applied on the face of the transfer after all other colors are printed (if such

other colors are desired) and the raised portions remain exposed as raised portions even after the transfer is applied, since the backing paper is removed by sliding the entire film (which may or may not constitute the 70 entire design) off the paper on to the article on which it is to be placed. The invention is particularly adapted to transparent effects where the background of the decalcomania is composed of a transparent film of cellulose 75 lacquer, spirit or oil varnish, and the design or lettering is superposed thereon in gold, silver, bronze, or other color. Where a transparent film is employed, the design and lettering stands out in exceeding bold and attractive relief, producing effects which have heretofore been unattained in the decalcomania art but required other arts for their production.

Of course, it is understood that opaque 85 backgrounds can also be used, made either of lacquer or oil colors, since the nature of the background in no way limits the invention. This is illustrated in Fig. 6.

I am aware that decalcomania has been 90 produced in the past in which an effort was made to simulate oil painting. In those cases, however, the decalcomanias were of the reverse or negative type, the colors being printed in the reverse order with successive printing on the back of the color film of white lead or other substances applied to those portions of the design which on the opposite face thereof were to indicate a more thickly applied paint. In this type of decalcomania 100 the slightly elevated portions did not stand out in bold relief and had no sharply defined edges definitive of a predetermined and accurately positioned outline, but the slightly raised portions appeared in the middle of 105 a field of color purely to suggest that the design was made by oil paint instead of being, as it really was, merely a printed design. Furthermore, that type of decalcomania required the use of varnish or size in the transferring operation in order to make the transfer adhere to the article, whereas in my invention the decalcomania is simply dipped in water, the film which carries the raised design slid off, and applied. Then again, in my 115 decalcomanias, the design, when transferred, appears precisely and exactly as it appeared on the decalcomania sheet, whereas in the decalcomanias of the prior art, to which I have referred, the fact that the thickening 120 material was near the surface of the article to which the design was applied than the colored layers of the design, caused distortion of the colored face because a part of it was pushed forward, while other parts remained 125 further back.

In decalcomania as produced by my invention, no imitation of any kind is desired, but relief effects are produced for their own sake and in such a way that an observer of the 130

decalcomania may know with complete and entire accuracy and precision exactly what design and color, sharpness of outline, degree of relief, etc. will appear on the article to which he intends to transfer the design. The relief effects produced by my invention have never been accomplished before in a decalcomania and the effect produced after the transfer is applied to the article is entirely novel and unique. The drawings accompanying this application are incapable of fully reproducing those effects, but if each line constituting the design of those drawings is imagined as being say in gold or bronze and as standing in bold relief, the attractiveness of the new decalcomania will be better appreciated.

I claim:

1. A positive decalcomania transfer comprising a transparent design-supporting lacquer film and supported upon the face thereof a design or lettering in flat colors said design including other portions in bold relief with respect to the film and to the said flat colors, the bold relief portions being constituted of material fused upon the design-supporting side of said film.

2. The method of producing decalcomanias which comprises coating a sheet of decalcomania paper with a water-soluble coating of adhesive character, applying thereto a lacquer layer of design-supporting capacity, printing a design upon said layer said design including portions constituted of sticky ink, dusting the surface while said sticky ink is still wet, with a powdered rosin compound, subjecting the thus produced product to heat adapted to bring the rosin compound to the melting point, and thereupon quickly withdrawing and cooling.

3. The method of producing decalcomanias which comprises coating a sheet of decalcomania paper with a water-soluble coating of adhesive character, covering the coating with a layer of lacquer, applying thereto portions of the design in flat colors, allowing said flat colors to become dry and hard, then printing other portions of the design in sticky ink, dusting the surface while said ink is still wet, with a powdered rosin compound, subjecting the thus produced product to heat adapted to bring the rosin compound to the melting point and thereupon quickly withdrawing and cooling.

4. The method of producing decalcomanias which comprises coating a sheet of decalcomania paper with a water-soluble coating of adhesive character, applying thereto a transparent lacquer layer of designed-supporting capacity, printing upon said layer a design including portions constituted of sticky ink, dusting the surface while said sticky ink is still wet, with a powdered rosin compound, subjecting the thus produced product to heat adapted to bring the rosin compound to the

melting point, and thereupon quickly withdrawing and cooling.

5. A decalcomania transfer comprising a sheet of decalcomania paper, a lacquer design-supporting film carried thereby and separable therefrom by the application of moisture, and, permanently supported upon the said film, a design or lettering including portions in bold relief constituted of material fused in situ.

6. A positive decalcomania transfer comprising a layer of paper, a layer of adhesive substance on said paper, a layer of lacquer on the face of said adhesive layer, and a design or lettering in bold relief constituted of material fused upon the lacquer.

7. A positive decalcomania transfer comprising a layer of paper, a layer of adhesive substance on said paper, a transparent layer of lacquer on the face of said adhesive layer, and a design or lettering in bold relief constituted of material fused upon the lacquer.

8. A positive decalcomania transfer comprising a layer of paper, a layer of adhesive substance on said paper, a layer of design-supporting lacquer on the face of said adhesive layer, and a design or lettering upon said lacquer layer and including portions in bold relief constituted of rosin containing material and fused and set into the bold relief condition while supported upon the lacquer layer.

In witness whereof I have hereunto set my hand.
